UNITED STATES PATENT OFFICE.

FRANKLIN C. PILLSBURY, OF WINCHESTER, MASSACHUSETTS.

MANHOLE-FRAME.

SPECIFICATION forming part of Letters Patent No. 689,224, dated December 17, 1901.

Application filed June 15, 1901. Serial No. 64,677. (No model.)

To all whom it may concern:

Be it known that I, FRANKLIN C. PILLSBURY, of Winchester, in the county of Middlesex and State of Massachusetts, have invented certain new and useful Improvements in Manhole-Frames, of which the following is a specification.

This invention relates to manhole-frames which surmount or cap street-manholes in sewers and other underground conduits and are provided with removable covers, the upper edge of the frame and the upper surface of the cover being substantially flush with the surface of the street in which the manhole is located. It not infrequently happens that owing to changes in grade or depression of the street-surface by wear the upper edge of the frame and the upper surface of the cover as originally adjusted are either raised above or depressed below the street-surface and require adjustment, it being desirable that the upper edge of the frame and the upper surface of the cover constitute parts of the street-surface without being either raised above or depressed below the surrounding surface.

My invention has for its object to make the cover and the cover-supporting portion of a manhole-frame vertically adjustable to compensate for changes that may take place in the level of the surrounding surface of the street.

To this end my invention consists in a manhole-frame which is extensible or telescopic in construction and comprises an annular fixed base member which rests on the masonry portion of the manhole and is non-adjustable and an annular movable member which supports the cover and is adapted to be rotated in the base member, said members being provided with means whereby the rotation of the movable member varies its height and the height of the cover relatively to the base member, said means being adapted to be interlocked to prevent accidental rotation of the movable member.

Of the accompanying drawings, forming a part of this specification, Figure 1 represents a plan view of a manhole-frame embodying my invention. Fig. 2 represents a side elevation of the same. Fig. 3 represents a perspective view, partly in section, of the base mem-

ber, the movable member being shown in dotted lines. Fig. 4 represents a perspective view of the movable member, the base member being shown in dotted lines.

The same reference characters indicate the same parts in all the figures.

In the drawings, *a* represents the annular base member of my extensible manhole-frame, said member having an outwardly-projecting flange 2 at its lower edge to rest on the masonry of a manhole. On the inner surface of the member *a* are formed a series of segments 3 of a helical rib or cam, three of such segments being shown in the present case, each being the equivalent of a part of a screw-thread.

b represents the movable member of the frame. This member is of considerably less diameter than the member *a*, so that it can occupy the space surrounded by the segments 3. On the outer surface of the movable member *b* are formed a series of segments 4, which are complementary to the segments 3, but are considerably shorter, the segments 4 bearing on the segments 3 and being inclined to conform to the pitch of the latter. The inclination or pitch of the segments 3 and 4 is such that when the member *b* is rotated the segments will coöperate in raising or lowering the member *b*, according to the direction of rotation. The segments 3 and 4 are provided with means, such as interlocking projections

5 and recesses 6, whereby they may be locked together to prevent accidental rotation of the member *b*, so that before said member can be rotated and vertically adjusted it is necessary to raise it sufficiently to disengage the segments 4 from the segments 3. The member *b* has an inwardly-projecting shoulder 7, which forms a seat for the marginal portion of the manhole-cover, the upper surface of the cover being flush with the upper edge of the member *b*. The member *a* is preferably provided with a narrow inwardly-projecting lip or flange 8, which partially covers the space between the members *a* and *b* and prevents the entrance of pebbles, &c., to said space.

9 represents a stop-lug formed on the flange 8 to abut against the highest segment 4 on the movable member when said member has reached the limit of its upward adjustment,

the said stop-lug preventing further rotation of the movable member in the direction required to adjust it upwardly. The segments 4 are thus prevented from moving off from 5 the higher ends of the segments 3.

10 10 represent stop-lugs formed at the lower ends of the segments 3 to limit in like manner the movement of the member *b* in the direction required to adjust it downwardly.

10. I claim—

1. An extension or telescopic frame comprising an annular fixed base member, an annular movable member, elongated screw-thread or helical cam-sections on the inner 15 surface of the fixed member, and complementary screw-thread or helical cam-sections on the outer surface of the movable member supported by the sections of the fixed member, whereby a rotary movement of the movable member varies its height relatively to the fixed member, said cam-sections having provisions for locking the two members together to prevent accidental rotary movement of the movable member.
2. An extension or telescopic frame comprising an annular fixed base member, an annular movable member, elongated screw-thread or helical cam-sections on the inner 20 surface of the fixed member, and complementary screw-thread or helical cam-sections on the outer surface of the movable member supported by the sections of the fixed member, whereby a rotary movement of the movable member varies its height relatively to the fixed member, the fixed member having inwardly-projecting stops arranged to abut against the higher ends of the cam-sections on the movable member and limit the upward 25 rotary movement of the movable member.
3. An extension or telescopic frame comprising an annular fixed base member, an annular movable member, elongated screw-thread or helical cam-sections on the inner 30 surface of the fixed member, and complementary screw-thread or helical cam-sections on the outer surface of the movable member supported by the sections of the fixed member, whereby a rotary movement of the movable member varies its height relatively to the fixed member, said sections having interlocking projections and recesses, whereby rotation of the movable member is prevented when the sections are interlocked, the sections of the movable member being separable from those of the fixed member to permit the adjustment of the movable member.

supported by the sections of the fixed member, whereby a rotary movement of the movable member varies its height relatively to the fixed member, said sections having interlocking projections and recesses, whereby rotation of the movable member is prevented when the sections are interlocked, the sections of the movable member being separable from those of the fixed member to permit the adjustment of the movable member.

3. An extension or telescopic frame comprising an annular fixed base member, an annular movable member, elongated screw-thread or helical cam-sections on the inner 45 surface of the fixed member, and complementary screw-thread or helical cam-sections on the outer surface of the movable member supported by the sections of the fixed member, whereby a rotary movement of the movable member varies its height relatively to the fixed member, the fixed member having inwardly-projecting stops arranged to abut against the higher ends of the cam-sections on the movable member and limit the upward 50 rotary movement of the movable member.

In testimony whereof I have affixed my signature in presence of two witnesses.

FRANKLIN C. PILLSBURY.
